(57) **CLAIM**

I claim the ornamental design for household containers, as shown and described.

DESCRIPTION

FIG. 1 is a perspective view of a household container in accordance with my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines formed by linear segments of equal length are provided for environmental purposes only and form no part of the claimed design.
